UNITED STATES PATENT OFFICE.

WATSON BEACH AND CLIFTON F. MCCLINTIC, OF DETROIT, MICHIGAN.

DISSECTING TABLE.

Application filed November 9, 1923. Serial No. 673,817.

To all whom it may concern:

Be it known that we, WATSON BEACH and CLIFTON F. MCCLINTIC, citizens of the United States, residing at Detroit, in the 5 county of Wayne and State of Michigan, have invented a new and useful Dissecting Table, of which the following is a specification.

This invention relates to a dissecting table, which is adapted for use in human anatomical laboratories.

The general object of the invention is to provide a table for this purpose having a top or platform of suitable dimensions and 15 adapted to support a cadaver in proper position for dissection, and having a tank adapted to contain a suitable preservative and normally supported beneath the platform, so that the cadaver may be lowered 20 therein when not being worked upon. Suitable mechanically operated cables, or other adjustable means, are provided for raising or lowering the platform to the desired position, and it is also desirable, but not necessary, to provide covers of specific construction 25 for closing over the tank when the cadaver is lowered thereinto, which covers may be swung downwardly out of the way beneath the table when the platform is raised.

30 The nature of the invention and the advantages thereof will be more fully explained in connection with the accompanying drawings, which illustrate the preferred form of the invention.

35 In the drawings:

Figure 1 is a perspective view of the invention with the platform lowered and one of the covers open.

Figure 2 is a vertical cross section of the 40 invention.

Figure 3 is a vertical longitudinal section thereof.

Figure 4 is an end elevation.

Figure 5 is a detail sectional view through 45 the tank, showing the means for supporting the same.

The table, which constitutes our invention, is mounted upon a rectangular frame having top side rails 10, connected by end 50 rails 11 and supported by posts 12, between which extend suitable braces 13. This frame is preferably made from iron tubing, such as is used for hospital beds, so that the same may be kept in sanitary condition. A plurality of straps 14, with their end portions 55 bent upwardly, are secured to the side rails

10, and form saddles for supporting a rectangular tank 15 within the frame. This tank is of sufficient size to entirely enclose a cadaver, and may be partially filled with 60 brine or other preservative, within which the cadaver may be immersed when not being worked upon, thereby to prevent decomposition and to keep the laboratory clean and sanitary. The tank 15 is provided in its bottom near one corner with a drain pipe 65 15.

The platform or top of the table 16 is of a shape and size to be freely received within the tank 15, and is preferably provided with 70 a peripheral reinforcing flange 17. Secured to the platform at each end thereof are eyes 18 to which the ends of cables 19 are secured, whereby the platform may be suspended at 75 any desired elevation. Each cable 19 is trained over a sheave 20, mounted in a bracket 21 secured to one of the end rails 11. The outer end of the cable extends downwardly and is secured to a yoke 22, which has outturned ends 23 journaled in the end 80 posts 12, one yoke being provided at each end of the frame. The intermediate portion of each yoke is provided with an outwardly extending crank or handle 24, which, when the yoke is swung downwardly and the platform 85 16 raised, may be secured underneath a spring hook 25, which is secured to one of the straps 14. Each yoke is curved inwardly, as shown at 33, so that when the yokes are lowered and the cadaver raised, as 90 shown in Figure 3, for dissecting purposes, the yokes will not be in the way of the student.

A pair of covers 26 are provided, having hinge straps 27 formed with eyes 28, which 95 are journaled on the respective side rails 10, and at their free edges one of the covers is provided with an upstanding flange 29, which fits within a channel shaped flange 30 on the other cover, when the covers are 100 closed. The covers are also provided with downturned flanges 31 at the ends which fit over the ends of the tank 15, and form a comparatively tight closure. These flanges 31 are provided with suitable notches 32, 105 through which the cables 19 may pass when the covers are closed.

From the foregoing description it will be seen that we have provided a convenient, practical and sanitary device for the purpose 110 described. The tank 15 is preferably removable from the saddle straps 14, so that all

parts of the device may be easily cleaned. When the student is working on a cadaver, the latter is supported, as shown in Figure 3, in a convenient position, and the yokes 22 are retained by the hooks 25. When the student has finished his laboratory session, the cadaver is lowered within the tank 15, where it will be completely preserved in exactly the same condition, until such a time as the student may desire to continue his work.

While we have shown and described the structure of the invention with considerable detail, it is to be understood that this is merely illustrative, and that many modifications may be made therein without departing from the salient features of the invention as expressed in the claims.

What is claimed is:

1. In a device of the character described, the combination of a frame having side and end rails, a tank normally supported within the frame, a platform provided with means for raising and lowering it within the tank, and covers hinged to the side rails and operating to form a closure over the top of the tank when the platform is lowered and swingable outwardly and downwardly into depending relation to their hinges so as to be out of the way when the platform is raised.

2. In a device of the character described, the combination of a frame, a tank adapted to be supported within the frame, a top or platform, cables by means of which the same is supported within the tank, sheaves over which the cables are trained, a yoke pivoted at each end of the frame and connected with the respective cables and operable when swung about its pivot to raise or lower the platform, and means for locking the yokes with the platform raised.

3. In a device of the character described, the combination of a frame having side and end rails, means for supporting a tank within the frame below said rails, a top or platform, cables by means of which the same is supported within the tank, sheaves over

which the cables are trained, means connected with the respective cables and operable to raise or lower the platform, and covers hinged to the side rails and movable to close the tank when the platform is lowered.

4. In a device of the character described, the combination of a frame, means for supporting a tank within the frame, a top or platform, cables by means of which the same is supported within the tank, sheaves over which the cables are trained, means connected with the cables and operable to raise or lower the platform, means for locking the last-named means with the platform raised, and covers hinged to the side rails and movable to close the tank when the platform is lowered, said covers having notches in their ends through which the cables may pass when the covers are closed.

5. In a device of the character described, the combination of a frame having end and side rails, means for supporting a tank within the frame below the rails, a top or platform, cables by means of which the same is supported within the tank, sheaves over which the cables are trained, a yoke pivoted at each end of the frame and connected with the respective cables and operable when swung about its pivot to raise or lower the platform, said yokes being curved so as to rest within the frame when the platform is raised, and means for locking the yokes in that position.

6. In a device of the character described, the combination of a frame, a tank supported within the frame, a platform within the tank, yokes pivoted to opposite ends of the frame and operatively connected to the platform to raise and lower the same within the tank, and means for locking said yokes to hold the platform in raised position.

In testimony that we claim the foregoing as our own, we have hereto affixed our signatures.

WATSON BEACH.
CLIFTON F. McCLINTIC.
